UNITED STATES PATENT OFFICE.

JOSEPH PARIS, OF NANTES, FRANCE.

SPACING FEED MECHANISM FOR WORK IN PUNCHING, DRILLING, OR LIKE MACHINES.

Application filed December 1, 1920. Serial No. 427,574.

To all whom it may concern:

Be it known that I, JOSEPH PARIS, a citizen of the Republic of France, and residing at Nantes (Loire Inférieure Department), 5 Route de Roche Maurice, in the Republic of France, engineer, have invented certain new and useful Improvements in Spacing Feed Mechanisms for Work in Punching, Drilling, or like Machines, of which the following is a specification.

This invention relates to a method and an apparatus permitting the rapid centering of structural members and various rolled bars upon a machine tool employed for instance for drilling or punching operations, whereby all previous marking of the pieces shall be obviated. For this purpose the pieces under operation are disposed in such manner as to slide between rollers whose position is closely adjustable with reference to the axis of the tool, or in other cases such pieces are rigidly secured to structural bars which are slideable between said rollers.

The accompanying drawing shows by way of example various constructional forms of an apparatus according to this invention.

Fig. 1 is a plan view of the devices employed for feeding an angle bar upon a punching machine.

Figs. 2 and 3 show respectively in side elevation and plan a device employed for drilling work upon a sheet metal piece.

In customary practice, the centres of the holes are determined by the intersection of 85 a line parallel to the edge of the piece, termed marking line, and a series of lines situated at right angles to the former and spaced according to determined dimensions.

In the process according to this invention, mechanical means are employed whereby the centre line and the successive perpendicular lines are caused to pass through the centre of the tool, without requiring such lines to be marked out in any way.

The bar 1, an angle iron for instance, is guided by the four rollers 2, 3, 4, 5 disposed in pairs upon the two plates 6 and 7.

The shafts of said rollers 4 and 5 are secured respectively to the plates 6 and 7, 50 while the shafts of the rollers 2 and 3 are mounted upon the arms 8 and 9 adapted to swing about the shafts 10 and 11 which are carried by the members 12 and 13 secured to the plates 6 and 7. The said arms 8 and 9 are drawn backwardly by the springs 14 and 15 in such manner that the bar 1 irre-

spectively of the thickness thereof shall always contact the rollers 4 and 5. It results from this disposition that the back edge of said bar can only move according to the tangent of these two rollers.

The distance between the rollers 4 and 5 and the axis of the tool is adjusted once for all by moving the plates 6 and 7 upon the main frame of the machine, and to permit 65 of this adjustment the plates may be provided with oval holes such as 16 having the clamping bolts inserted therein. The operation is carried out in such manner that the distance d between the tangent to the 70 rollers and the axis of the tool a shall be equal to the distance between the holes to be formed and the back edge of the bar 1. Under these conditions, upon sliding said bar between the rollers, the centre line of 75 the proposed holes will invariably coincide with the centre of the tool.

It should be remarked that in case the bar 1 should not be perfectly straight, no inconvenience will follow therefrom inasmuch as the customary trimming of the bar will be sufficient to permit said bar to be considered as straight upon the distance between the rollers, which can in fact be made very short,

Any possible errors in centering will fall within the limits of the precision required for structural steel work and the like.

This being accomplished, when it is desired to bring the centre of a hole upon the 90 axis of the tool, all that is necessary is to fix with reference to the tool the point on the edge of the bar which is located upon the same cross section as the said centre of the hole. To this end a template 17 is secured 95 to the bar 1, for instance by small clamps, and a pointer 18 is disposed upon the machine frame in line with the tool.

The template 17 carries a series of lines corresponding to the distance between 100 centres of the holes, the said lines being brought successively opposite the pointer. The bar is drawn along by rotating one of the rollers mounted on a fixed shaft 5, for instance by means of a hand wheel 19, said roller being 105 provided with a striated or fluted surface for drawing along the bar.

The operation of the device is as follows:

The distance between the rollers 4 and 5 and the tool having been adjusted as above 110 mentioned, the template ruler 17 is secured at both ends thereof of the said bar, the

workman operates the hand wheel 19 in such manner as to draw along the piece and to bring marking lines successively opposite the pointer 18; as each line comes into position, he stops the hand wheel 19 and couples on the machine for producing the hole.

Figs. 2 and 3 show the use of the same method in the case of sheet metal or large plates. In this case the sheet metal piece 20 is secured to an angle iron bar which is disposed and guided exactly in the same manner as above indicated. The said angle iron is of an average section whereby it shall be sufficiently rigid and at the same time can be caused to bend under an effort which is easily obtainable by a person acting upon the end of said bar. The clamps 22 are disposed upon the angle bar 1 at frequent intervals, said clamps being provided with the clamping screws 23 and the stop pieces 24 all of which are fitted with tempered steel points. The distance between said points and the back edge of the angle bar is exactly the same for all the clamps.

The sheet metal piece under operation is secured to the angle bar 1 by means of the said clamps. Along the edge of the sheet metal piece is marked out for instance by a chalked cord a straight line upon which are brought the points of all the clamps, the latter being operated with sufficient force to cause the said points to enter the sheet metal. With the points thus ranged in line, the rear side of the angle bar is now exactly in the straight position. The rollers 25 support the sheet metal piece 20 in such manner as to permit of readily moving the latter.

The work on the piece is carried out in the same manner as in the preceding case. The said template 17 is secured along the edge of the angle bar; the marking lines of said template are arrested successively opposite the fixed pointer 18, which permits of drilling or punching a series of holes disposed in a straight line and spaced in the same manner as the lines on the template. To cause different parallel lines to pass in line with the tool for the purpose of forming various rows of holes such as is usually carried out in sheet metal work, the entire assemblage of the guide rollers is carried upon a plate 28 movable in grooves which are situated perpendicular to the centre lines of the fixed rollers. The said plate is moved by a screw 29 actuated by a hand wheel 30, and the plate may be secured in any desired position by suitable set screws. Upon the side of the plate 28 is disposed a pointer 31 cooperating with a template 32 secured to the machine frame 33. The template 32 is preferably provided with different colored lines corresponding to the various rows of holes to be formed.

The method of operating is as follows:
65 The hand wheel 30 is actuated to bring

the pointer 31 opposite the line on the template 32 corresponding to the row of holes to be formed, for instance a red line. The hand wheel 19 controlling the actuating roller is then operated to bring the sheet metal piece under the tool at the same time that the template 17 is brought opposite the pointer 18, and each time that one of the red lines of said template comes into position, the movement is stopped and the machine is put in operation. It should be remarked that the work can be carried out without requiring any previous trimming of the edges of the sheet metal piece.

Claims.

1. The combination, with a drilling or punching machine, of a guiding and centering device for the pieces under operation, comprising an angle bar serving as a support for said pieces and longitudinally movable, the vertical portion thereof being downwardly directed, two finely fluted stationary rollers serving as bearing members for the rear side of said angle bar and also as means for moving the same, two movable rollers mounted upon swinging arms which are drawn back or pressed against the said angle bar by springs, a template carrying lines corresponding to the space between centres of the holes to be formed and secured to said angle bar, a pointer disposed upon the machine frame and cooperating with said lines of the template, two plates carrying said fixed and movable guiding rollers and provided with oval shaped holes, clamping bolts disposed in said holes and secured to the machine frame permitting the movement of said plates for adjusting the distance between said rollers and the axis of the tool, and a hand wheel mounted upon, 105 the shaft of the fixed rollers and adapted for the hand operation of said rollers.

2. The combination, with a drilling or punching machine, of a spacing feed mechanism, comprising an angle bar serving as a support for said pieces and longitudinally movable, clamps secured to said angle bar at frequent intervals, clamping screws disposed at the upper part of said clamps, stop pieces, said clamps serving as means for securing material to be operated upon to said angle bar, and rollers situated below the piece under operation for the purpose of supporting the same.

3. The combination, with a drilling machine, of a spacing feed mechanism, comprising an angle bar serving as a support for said pieces and longitudinally movable, guiding rollers for said angle bar, a movable plate supporting the said guiding rollers and movable in a direction perpendicular to the centre line of the fixed rollers, a screw for moving the said plate, a hand wheel secured to said screw for the hand operation thereof, a pointer disposed upon the side of said plate, 120 a

and a template secured to the machine frame for indicating the movement of said plate.

bolts passing through the said holes and secured to the machine frame, providing for the movement of the said plates in order to change the distance between the said rollers and the axis of the tool, and a hand-wheel secured to the axle of the fixed rollers for the hand control of the same. 55 60

4. The combination, with a drilling or
punching machine, of a spacing feed mech-
anism, comprising a longitudinally movable
angle bar, two juxtaposed guiding rollers,
one of said rollers being slidable with easy
friction upon the hub of the second, a hori-
zontal shaft situated perpendicular to the
10 direction of longitudinal movement of said
angle bar and carrying the said guiding
rollers, two rollers supporting said shaft
which latter is caused to bear upon the sharp
edges of triangular grooves, rods for main-
15 taining said supporting rollers in spaced re-
lation, and a plane surfaced roller path for
said supporting rollers.

5. The combination, with a drilling or
punching machine, of a spacing feed mech-
anism, comprising a longitudinally movable
20 angle bar having a recess upon each side and
at each end, a template disposed upon said
bar, jaws engaging the recesses at the sides
of the angle bar, an adjustment screw dis-
25 posed upon each of said jaws for engaging
the recesses at the ends of the bar whereby
said template shall be maintained in place.

6. The combination with a drilling or
punching machine, of a spacing feed mech-
anism comprising guiding means, elements
30 guided by the said guiding means and adapt-
ed to support the pieces of work, clamping
elements having screws with tempered points
and adapted to be attached on the one hand
35 to the piece of work according to a straight
line drawn in advance and on the other hand
to the said guided elements, the latter being
constituted by an angle iron member mov-
able lengthwise whereof the vertical flange is
40 downwardly extending, the guiding means
being constituted by two fixed rollers with
fine fluting, serving as a support for the back
of the said angle iron member and as a dis-
placing means and by two movable rollers
45 which are caused to bear upon the said angle
iron member by springs, a template provided
with marking lines corresponding to the
distance between the centers of the holes to
be drilled and secured to the angle iron
50 member, a pointer secured to the machine
frame and co-operating with the lines of the
template, two plates carrying the said fixed
and movable guiding rollers and having
oval-shaped holes formed therein, attaching

7. The combination with a drilling or
punching machine, of a spacing feed mech-
anism comprising guiding means, elements
guided by the said guiding means and adapt-
ed to support the pieces of work, clamping
elements having screws with tempered points
and adapted to be attached on the one hand
to the piece of work according to a straight
line drawn in advance and on the other hand
to the said guided elements, a template pro-
vided with marked lines corresponding to the
distance between the centers of the holes to
be drilled and secured to the guided ele-
ments, a pointer secured to the machine
frame and co-operating with the lines of
the template, two plates carrying the said
guiding means, and means for changing the
distance between the guiding means and the
tool of the drilling or punching machine. 80

8. The combination with a drilling or punching machine, of an angle bar, guiding means for said angle bar, a template constituted by a ledge carrying lines being spaced in a suitable manner, fixing means adapted to secure said template upon said angle bar in a removable manner and a fixed pointer before which the said template will be displaced.

9. The combination with a drilling or 90
punching machine, of an angle bar, guiding
means for said angle bar, a template consti-
tuted by a ledge carrying lines being spaced
in a suitable manner, fixing means adapted
to maintain the said template upon the said 95
angle bar in a removable manner, rotary
driving means acting upon the said angle
bar in order to displace the same and a fixed
pointer before which the said template will
be displaced. 100

In testimony, that I claim the foregoing as my invention I have signed my name in presence of two subscribing witnesses.
